DOOR CHECK

Frederick Albert Masson, Winnipeg, Manitoba,
Canada

Application May 6, 1938, Serial No. 206,449

4 Claims. (CL. 16—49)

Door checks, at present on the market, are usually of the oil type which, in operation, permit the quick opening of a door under manual pressure and when released, to swing back to within a short distance of final closing, at which time the door is slowed up to prevent a heavy slam. Such door check control is due to the movement of oil within the check casing, which is moved by a coil spring having a built up tension therein.

When such door checks are new and properly adjusted, they will work well but when, in time, the parts wear and the oil depreciates, preventing its proper function, they are always in the repair shop.

The principal objects of the present invention are to provide a mechanically operated door check which will do the same work as the oil operated check and at the same time stand up under years of service.

A further object of the invention is to control the door closing speed with a governor which can be easily regulated for various speeds.

A further object of the invention is to provide a spring means for returning the door which can be quickly tensioned for varying weights of doors.

A further object of the invention is to enclose the mechanical parts in a dust proof casing which can be quickly opened for repair purposes.

Still further objects of the invention are to provide means for utilizing the door check for either left or right hinged doors and for fastening the check either on the door or the door frame with equal efficiency.

With the above important objects in view which will become more apparent as the description proceeds, the invention consists essentially in the arrangement and construction of parts herein-after, more particularly described, reference being had to the accompanying drawing in which;

Figure 1 is a perspective view of a door and door frame with the invention in position.

Figure 2 is an enlarged horizontal section taken on the line 2—2, Figure 1.

Figure 3 is a vertical sectional view taken on the line 3—3, Figure 2.

Figure 4 is a partial horizontal sectional view taken on the line 4—4, Figure 3.

Figure 5 is an enlarged plan view of the crank and lever linkage.

Figure 6 is a plan view of the ratchet drive unit showing the dog restraining lever.

In the drawing, like characters of reference indicate corresponding parts in the several figures.

A framework 1 encloses a door 2, hinged at 3 to the framework. A rectangular shaped boxing 4

is secured to the upper part of the door by screws 5, said screws passing through side extension plates 6 and 7. The upper part of the boxing is closed by a plate 8, fastened by screws 9 at the corners. A circular cup shaped casing 10 is inverted and fastened interiorly and at one corner to the bottom of the boxing with screws 11, said screws passing through an annular ledge 12 on the edge of said casing. A ribbon spring 13 is wound within the casing and has one end fastened to a spindle 14 which passes through the casing, through the bottom and closure plate of the boxing and has the projecting ends squared as at 15. The outer end of the spring is fastened to the inner side of the casing.

A gear wheel 16 is rotatably mounted on the spindle above the casing and is spaced therefrom by a washer 17. A ratchet wheel 18 is fastened to the spindle above the gear wheel and is adapted to be engaged by a dog 19 pivoted on the face of the gear wheel 16 and held in engagement by a flat spring 20.

The gear wheel 16 meshes with a pinion 21 fastened by a set screw 22 to a shaft 23, and said shaft is rotatably mounted in bearings in the bottom and closure plate of the boxing 4. This shaft is provided with a worm wheel 24 which meshes with and drives a worm shaft 25 mounted in slideable bearings 26 and 27 carried in the sides of the boxing and held in place by set screws 28 and 29. The worm shaft is provided with a governor 30 having one end fixed to the worm shaft and the other end slideable thereon and provided with a disk 31 adapted to contact a friction leather 32 carried by a bell crank 33 pivotally mounted on a bracket 34 on the interior side of the boxing. This bell crank is normally held away from the disk 31 by a spring 35 which hooks on one side of the crank, encircles the pivot pin thereof and terminates on the interior side of the boxing wall. A set screw 36 passes through the side of the boxing and contacts with one of the levers of the bell crank for adjusting purposes.

From the above arrangement, it will be obvious that if the spring 13 is wound up and rotates the spindle 14, the governor will be rotated, causing the disk 31 to move into contact with the friction leather 32. By adjusting the set screw 36, the speed of the governor can be regulated and accordingly, the speed of the spindle.

A crank 31, having a square hole at one end, is fastened to the upper squared end of the spindle 14 by tightening a bolt 38 to close the forked ends of the crank. The other end of the crank is pivoted at 39 to a lever 40 which passes back over

the boxing and is pivoted to a bracket 41 fastened by screws to the door framework 1.

From the above arrangement, it will be observed that when the door is opened, the crank 37 will rotate in a clockwise direction and wind up the spring 13 while the ratchet wheel 18 will click past the dog 19. When the door is released, the spring 13 will cause the door to swing back until the dog engages the ratchet wheel and the speed of the governor will then regulate the final closing speed of the door.

The ratchet wheel 18, shown in Figure 4 of the drawing, is provided with six teeth. In this connection, it will be understood that various numbered teeth could be employed to suit the requirements of the trade. Door checks having such a ratchet wheel arrangement would be preferably used on interior doors where a long slow closing movement might be desirable. On outside doors where cold or heat is to be excluded, it would be necessary to have the door swing back to within a few inches of final closing before the governor started to work. In such cases a ratchet wheel having finer teeth, such as shown in Figure 6 would be employed. Above the ratchet wheel, and rotatable on the spindle, would be a loose lever 42 having the circular part around the spindle dished upward to tensionally engage the closure plate 8. As the lower edge of the dish would have more frictional contact with the ratchet wheel than the upper part with the closure plate, the lever would turn with the ratchet wheel until an obstruction was reached. The other end of the lever is provided with a downwardly extending pin 43 which rides in a cam shaped slot 44 in the dog 19. The end of the slot, adjacent the pivot point of the dog, is slightly wider than the pin 43 so that the dog is free to move slightly when the pin is at that end.

In operation, when the door is opened, the dog will ride freely up and over the ratchet tooth and then move in to the next tooth. The pin 43 will then contact the cam slot and move the dog clear of the ratchet for the balance of the door opening. When the door returns the pin 43 will hold the dog clear in exactly the reverse manner so that the dog will contact the ratchet wheel for the movement of only one tooth and the final movement of the door under governor control will be for only that amount.

By releasing the crank 37 at the pivot point 39, it can be swung around in either direction to increase or reduce the tension in the spring 13 to conform to the weight of the door. At such time, the friction lever 42 will be stationary at the corresponding end of the cam slot. The crank 37 may be fastened to the bottom end of the spindle if it is desired to place the boxing on the door framework or the boxing may be reversed with the closure plate at the bottom if the opposite rotation of the crank is required.

While I have shown the present arrangement of the various parts of the invention, it will be understood that the design of the mechanism may be altered to form a more compact construction without departing from the spirit of the invention.

What I claim as my invention is:

1. A door check comprising a spring actuated spindle rotatably mounted in the frame of said door check, said spindle adapted to tension said spring in its rotation, a mechanical governor rotatably mounted in said frame and operated by said spring through a ratchet and dog, means for disconnecting said governor from said spring during the tensioning of same, means for releasing said dog from said ratchet for a pre-determined number of teeth during the de-tensioning of said spring and then connecting said dog to said ratchet to drive said governor for the remaining de-tensioning of said spring. 20

2. A door check having a spring actuated spindle, a mechanical governor driven from a ratchet on said spindle through a dog, means carried by said spindle and operable on said dog for releasing said dog from said ratchet in the tensioning 25 of said spring, and means adapted to maintain said dog disconnected from said ratchet for a pre-determined number of teeth in the de-tensioning of said spring and to connect said dog to said ratchet for the final de-tensioning movement of said spring.

3. A door check having a spring actuated spindle and said spring being tensionable on the rotation of said spindle, a mechanical governor driven by a ratchet on said spindle through a 35 dog, a lever pivoted on said spindle and frictionally driven thereby, said lever provided with means operable on said dog to permit said dog to ride the teeth of said ratchet for a pre-determined spring tension rotation of said spindle and 40 then to free said dog from the remaining teeth of said ratchet for the remaining spring tensioning rotation of said spindle, and to return said dog into contact with said ratchet in the reverse manner upon the de-tensioning rotation of said 45 spindle. 50

4. A door check having a spring actuated spindle, and said spring being tensionable on the rotation of said spindle, a mechanical governor driven by a ratchet on said spindle through a dog, a lever pivoted on said spindle and frictionally driven thereby, said lever provided with a pin operable in a slot on said dog to permit said dog to ride the teeth of said ratchet for a pre-determined spring tension rotation of said spindle and then to free said dog from the remaining teeth of said ratchet for the remaining spring tensioning rotation of said spindle, and to return said dog into contact with said ratchet in the reverse manner upon the de-tensioning rotation of said 60 spindle. 55

FREDERICK ALBERT MASSON.
